FIG. 1

FIG. 2

FIG. 3

FIG. 4

FIG. 5

FIG. 6

Fig. 1 is a perspective view of a combined food and bottle warmer embodying my new design;

Fig. 2 is a front elevational view of the combined food and bottle warmer on a reduced scale;

Fig. 3 is a side elevational view thereof;

Fig. 4 is a top plan view of the combined food and bottle warmer;

Fig. 5 is an enlarged fragmentary sectional view taken substantially along the line 5-5 in Fig. 4; and

Fig. 6 is a similar horizontal sectional view taken substantially along the line 6-6 in Fig. 2.

The side of the combined food and bottle warmer opposite that illustrated in Fig. 3 is like the side shown in Fig. 3, and the back of the combined food and bottle warmer is like the front thereof illustrated in Fig. 2.

I claim:

The ornamental design for a combined food and bottle warmer, substantially as shown and described.
